FORM-REGISTERING BOX FOR COLOR PRINTING.

Application filed May 20, 1921. Serial No. 471,161.

To all whom it may concern:

Be it known that we, CLARENCE A. BETTS and CHARLES S. OTT, citizens of the United States, residing at Kansas City, in the county of Jackson and State of Missouri, have invented a new and useful Form-Registering Box for Color Printing, of which the following is a specification.

Our invention relates to form registering boxes for color printing, and particularly to a device of this character which is used in printing offices for registering forms for printing presses to obtain perfect registry of colors.

It is our experience that color printing from plates on printing presses requires considerable expenditure of time and necessitates the assistance of at least three men to lock the forms, to manipulate the forms to make registry, and to pull an impression to try the registry, beside, pulling off the press from twenty five to five hundred strike sheets to be used in obtaining proper registry. The form must be taken from the press, compared with the strike sheets, adjustments made, impressions pulled, time and time again and until the exact register is obtained. When forms are registered on different types of proof presses it is not possible to obtain an absolutely perfect register of colors and the attempt involves a great waste of paper stock in repeatedly trying out the register which, at best, is a try-out practice.

The object of our invention is to provide a form register box for receiving the printer's form and for, thereafter, manipulating the form in the box to promptly and accurately obtain perfect register of the form to effect perfect register of the color scheme and, thereby, save time and delay, save paper stock, and save the expense of assistants.

We attain these objects and other advantages by means of the mechanism and combination of parts illustrated in the accompanying drawing in which—Figure 1, is a top plan view of a form registering box embodying our invention; Figure 2, is a front elevation of the same, and showing the lid raised to a vertical position; Figure 3, is a transverse section of the same, on the line 3—3, in Figure 1; Figure 4, is a cross section of the lid of the box, on the line 4—4, in Figure 2; Figure 5, is an end eleva-

tion of the box and its lid, and Figure 6, is a top view of a fragmentary end of the box proper.

Similar numerals of reference refer to corresponding parts throughout the several views.

Referring to the drawings—the form registering box 1, is made of wood or metal, preferably of wood because of the light weight thereof and adaptation for easy transport. The box is arranged to receive the printing form on its floor 2, so that the engraving of the form will closely approach the inner side of its lid. The floor member 2, is formed solid and on the sides of the member are suitably fastened side members 5, and on the ends of the member are fastened end members 6, the side and end members are fastened on the floor member by screws 7. Centrally disposed in the box is a color printing form 8, which is locked in a chase 9, the quoins 10, and furniture 11, holding the form in proper position in the chase. Between the sides and ends of the chase 9, are arranged pieces of furniture 12 which are spaced suitably from the inner sides of the box to permit shifting adjustments thereof to hold the chase in any desired position. In the side members 5, and end members 6, are suitably imbedded posts 13, two in each side member and one in each end member, which posts are located suitably for receiving first, a bore provided with screw threads and then, winged screws 14 which are operatively engaged by the screw threads in the posts. The screws 14, are of a suitable length to pierce through the sides and ends of the box and the posts 13, and extend inwardly of the box a distance calculated to provide ample space for adjusting the furniture 12, and thereby adjusting the form to any desired position.

The box 1, is provided with a lid 15, which is hingedly mounted on the box by a plurality of hinges 16. The lid comprises a frame 17, having the inner portion of its lower sides excavated to receive a plate of glass 18, and beneath the glass a sheet of transparent material, in this instance, a sheet of transparent celluloid 19, which is held to press upon the glass by transversely extending tensioned straps 20, the terminals of which are convexed to form bearings 21, the straps being movably held to bear on the

celluloid sheet by elongated plates 22, which are attached on the lower side of the side members of the frame 17, by screws 23, in the well known manner.

- 5 In Figure 1, the form shown comprises four plates for printing a two color cartoon and, for the purpose of properly illustrating and describing the modus operandi, one form only is provided with engraved 10 letters and border. The solid color is blue 24, and the border 25, is orange, as also are the letters 26. One color is printed as the key color and the other color should register perfectly with the key color.
- 15 When using the form register box the color forms are locked in the chase 9, with enough furniture around the chase to allow suitable space on all four sides, to shift the form to obtain perfect register. An impression of the form is then taken on transparent celluloid sheet 19, in any suitable manner, the impression taken forms the key 20 for the other colors. To register the other colors the form is placed in the register 25 box and properly disposed therein, as above mentioned, and the lid of the box closed down, thus bringing the celluloid sheet to 30 closely bear on the form. The several adjusting screws are then manipulated to adjust the form as closely to the key impression as possible. If the register is not thereby perfect the form plates in the chase 9, are moved and swung to effect the perfect 35 register of the form with the key color on the celluloid sheet. When making the adjustments mentioned the form is clearly visible to the operator through the glass 18 and transparent celluloid 19, and the latter impinging fairly upon the form he can 40 readily determine the adjusting movements to be made to obtain a perfect register, which movements of the form plates are noted and designated by wax pencil marks on the glass 18. The lid is raised and the 45 moves indicated by the pencil marks are made in the form plates and the operation repeated until a perfect register is obtained. The register box requires the attention of one man only and the time for making an 50 actually perfect register is reduced upwards of one half the time required and consumed by the old method of registry, and a far greater degree of accuracy of register is effected than is possible by any other method. The register box is also useful in making 55 register of forms for the electrotype foundry.

Having described our invention what we claim is—

1. A form register box for color printing, consisting of a shallow box adapted for receiving a printing form, a lid hingedly mounted on said box, said lid comprising a frame provided with a glass plate and with a sheet of transparent material bearing 65 on the lower side of the glass plate and adapted for bearing on a printing form lodged in said box, furniture slidably arranged in said box, and a plurality of press screws operating in the sides and ends of 70 said box and adapted for moving said furniture to shift said printing form.

2. A form register box for color printing, consisting of a shallow box adapted for receiving a printing form, a lid hingedly 75 mounted on said box, said lid comprising a frame provided with a glass plate and with a sheet of transparent material on the lower side of the glass plate and adapted for bearing on a printing form lodged in said box, 80 furniture slidably arranged in said box, a plurality of press screws operating in the sides and ends of said box and adapted for moving said furniture to shift said printing form, and a plurality of tensioned strips 85 slidably arranged on said lid and adapted for holding the transparent material in place.

3. A form register box for color printing, consisting of a box adapted for receiving 90 a printing form, a lid hingedly mounted on said box, said lid comprising a frame provided with a sheet of transparent material adapted for bearing on said printing form when the lid is closed on the box and having 95 impressed thereon a key impression of the form, and means associated with said box adapted for registering said printing form with the key impression thereof on the transparent material on said lid. 100

4. In a form register box for color printing, the combination with the box, of a lid hingedly mounted on the box, said lid comprising a frame provided with a sheet of transparent material bearing thereon a key 105 impression of a printer's form, and means arranged on the box for moving said form to register with the impression thereof on the transparent sheet on said lid.
